UNITED STATES PATENT OFFICE.

ANDRÉ LÉON VICTOR CLÉMENT DEBRIE, OF PARIS, FRANCE.

STAND FOR CINEMATOGRAPHIC AND PHOTOGRAPHIC VIEW TAKING APPARATUS.

Application filed September 20, 1926, Serial No. 136,668, and in France December 4, 1925.

The usual stands for cinematographic and photographic view taking apparatus or for geodesical apparatus and such like comprise a platform supported by a certain number 5 of pivotally mounted legs (generally three) the length of which is generally adjustable. The best stands used up till now are generally provided with forked legs, the forks of each leg being secured to two points comparatively near to each other and never to 10 two opposite points with reference to the center of the platform. The result of such a construction is that the stand is not steady inasmuch as each leg is secured sideways and 15 is attached only to a small part of the periphery of the platform.

My invention has for its object a stand which avoids this drawback. It is characterized by the fact that the parts along 20 which the ends of the fork of each leg are secured to the platform are at two opposite ends of a diameter of the platform.

On appended drawings:

Figs. 1 and 2 give diagrammatically and 25 by way of example a form of execution of my improved stand, Fig. 1 being a plan view and Fig. 2 a perspective view thereof.

The platform 4 has the shape of a regular polygon having an even number of sides, of 30 a dodecagon, for instance as shown on the drawing, the center being at 5. The legs 6 the tops of which are forked are pivotally secured to two opposite sides of the polygon and can be held tightly in the desired position 35 by means of wing nuts 7 screwed on to the threaded spindles 8 around which the extremities of the forks are adapted to pivot.

It can be seen that the improved stand shows a very great steadiness and that the platform cannot move with reference to the 40 legs nor warp.

The setting up and the folding of the stand are very easy as the legs slide with reference to each other along flat surfaces.

Evidently I have only described a dodecagonal platform by way of example. Any 45 other polygon, such as a hexagon, having an even number of sides can be used as well. Also the two opposite sides to which are secured the two legs of one same fork can be 50 unequally spaced from the centers.

What I claim is:

1. Stand for cinematographic and photographic apparatus and the like comprising a platform, a number of legs and a fork ending each leg, the two ends of each fork being secured to the platform at two points the line connecting which passes through the center of the platform. 55

2. Stand for cinematographic and photographic apparatus and the like comprising a platform having the shape of a polygon of an even number of sides, a number of legs and a fork ending each leg, the two ends of each fork being secured to two opposite sides 60 of the polygonal platform at two points the line connecting which passes through the center of the platform. 65

In testimony whereof I have signed my name to this specification.

ANDRÉ LÉON VICTOR CLÉMENT DEBRIE.
